UNITED STATES PATENT OFFICE.

ALLEN PAUL HEIDT, OF BAY SHORE, NEW YORK.

SASH-LOCK.

SPECIFICATION forming part of Letters Patent No. 634,213, dated October 3, 1899.

Application filed November 25, 1898. Serial No. 697,306. (No model.)

To all whom it may concern:

Be it known that I, ALLEN PAUL HEIDT, a citizen of the United States, residing at Bay Shore, in the county of Suffolk and State of

5 New York, have invented certain new and useful Improvements in Sash-Locks for Windows, of which the following is a full and complete specification, such as will enable those skilled in the art to which it appertains to 10 make and use the same.

This invention relates to sash-locks for window-sashes; and the object thereof is to provide an improved device of this class which may be used in connection with ordinary 15 counterbalance-weights and cords or without such devices, and by means of which either the upper or the lower sash may be locked in a closed position or said sashes adjusted to any desired position for ventilation or other 20 purposes.

The invention is fully disclosed in the following specification, of which the accompanying drawings form a part, in which—

Figure 1 is an inside view of a part of one 25 side of a window-frame, showing one form of my improved locking device connected therewith, part of the construction being shown in section, and a separate locking device being provided for each sash; Fig. 2, a section on 30 the line 2 2 of Fig. 1; Fig. 3, a side view of a casing which is countersunk in the window-frame and in which part of the locking devices is mounted, said casing being detached from the frame; Fig. 4, an edge view of that

35 part of the window-frame shown in Fig. 1; Fig. 5, a view similar to Fig. 1; showing a modified form of construction, in which one locking device is employed for both sashes; and Fig. 6, a section on the line 6 6 of Fig. 5.

40 In the drawings forming part of this specification the separate parts of my improvement are designated by the same numerals of reference in each of the views, and in said drawings, reference being made to Fig. 1, I 45 have shown at 7 a part of one side of a window-frame, and said frame is provided with the usual vertical spaces 8, in which the sashes are mounted, the sashes being not shown and said spaces being separated by the 50 usual central bead or strip 9 and being formed by said central bead or strip 9 and the outer bead or strip 10 and the inner strip 11.

In Figs. 2 and 6 I have shown the sashes 12 or parts thereof, and each of these sashes is in practice provided at one side with a rack- 55 bar 13. (Clearly shown in Fig. 2.)

I will first describe the locking device applied to the lower sash and mounted in the right-hand space 8, as shown in Fig. 1 and shown in section in Fig. 2, and in this form of 60 construction I countersink in the frame a casing 14, which is oblong in form and provided with a central oblong chamber 15, through which passes a tubular shaft 16, which is also countersunk in the side of the frame 65 and covered by the inner bead or strip 11, and said tubular shaft is provided with a cam 17 and secured transversely of the casing 14 below the shaft 16, as shown in Fig. 2, and at the right of Fig. 1 is a fulcrum-pin 18, and 70 mounted in the casing 14 is a locking-lever 19, which is fulcrumed on said pin 18 and the lower end of which is provided with a head 20, between which and the inner wall of the casing 14 is placed a spiral spring 21. The spiral 75 spring 21 operates normally to force the lower end of the locking-lever 19 outwardly and the upper end thereof inwardly, and said lever projects upwardly and is curved to correspond with the cam 17, over which it passes, when 80 the parts are in the position shown in Fig. 2, and the upper end thereof is provided with an outwardly-directed lug or projection 22, which is adapted to operate in connection with the rack-bar 13 on the sides of the adjacent sash.

Secured to the inner surface or edge of the frame 7 is a plate 23, provided with keyholes 24, and I also provide a key 25, having a shank 27, adapted to be inserted into the keyholes 24. 90

The end of the tubular shaft 16 is angular in cross-section, as shown in Fig. 3, and the inner end of the shaft 27 is similar in form and adapted to enter said tubular shaft, and the tubular shaft 16 is provided with a spring 95 28, which is wound thereon and one end of which is secured thereto and the other to the casing 15 at 29.

The locking device for the upper sash (shown at the left of Fig. 1) is precisely the 100 same as that for the lower sash, with the exception that the fulcrum-pin 18 for the lever 19 is placed in the upper portion of the chamber 15 and the free end of said lever

projects downwardly, and the key for each of said devices is the same, and in the normal position of each of said locking devices the springs 28 turn the tubular shaft 16 into the position shown in Fig. 2, in which position the cams 17 force the free ends of the levers 19 outwardly and they engage with the rack-bars 13, and the sashes are locked in whatever position they may be in.

10 In order to release the locking device, so as to raise or lower the sashes, the keys 25 are turned to the right, and the tubular shaft 16 is turned correspondingly in the direction of the arrow shown in Fig. 2, and the cams 17 are turned to the right, and the springs 21 force the free ends of the levers 19 inwardly, so that the lugs or projections 22 thereon are disconnected from the rack-bars 13, and the sashes may be raised or lowered, as will be 15 readily understood. In order to hold the tubular shaft 16 in this position, the keys 25 are provided with lugs or projections 30, which are turned so as to enter a notch or recess 31, formed in the perimeter of the keyholes 24, 20 and all that is necessary in order to operate the tubular shaft 16, as described, is to insert a key, as shown in Fig. 1, and turn the same and then slide the lug or projection 30 into the notch or recess 31, it being understood 25 that the key-shank 27 is free to slide in the tubular shaft 16, and when the lug or projection 30 is removed from the notch or recess 31 the spring 28 forces the shaft 16 back into the position shown in Fig. 2, and the cam 17 30 forces the lever 19 outwardly, and the corresponding sash is again locked.

In Fig. 1 I have shown but one of the keys 25; but, as hereinbefore stated, it will be apparent that both of these are of the same form, and it will also be apparent that the locking device for the upper sash (shown at the left of Fig. 1) or the separate parts thereof may be arranged in the same manner as those for the lower sash at the right of Fig. 1 45 and in Fig. 2 without in any wise altering the construction of the parts, the arrangement of the lever 19 and the direction in which the shaft 16 is turned being simply reversed.

In Figs. 5 and 6 I have shown a modified 50 form of construction in which a single locking device is provided for both sashes, and in this form of construction the casing 15 is countersunk in the frame beneath the central bead or strip 9, and the locking-lever 19 is 55 provided at its free end with a cross-head 32, which operates in connection with the rack-bars 13 of each sash. The frame 7 is also provided with a transverse chamber 33, in which the cross-head 32 works, and the bead 60 19 is cut away transversely of its inner side, as shown at 34, for a similar purpose. With these exceptions the locking device shown in Figs. 5 and 6 is exactly the same as each of those shown in Fig. 1, the difference being 65 that by reason of the cross-head 32 on the locking-lever and the position of said lever a

single locking device is adapted to operate in connection with both sashes. It will also be seen on an examination of Fig. 2 that the lever 19 is provided rearwardly of its fulcrum-pin 18 with a backwardly-directed pointed projection 19^a, and if at any time the spring 21 should break or for any reason become useless the lever 19 may still be operated by the cam 17 by turning the shaft 16 so that the point 17^a of said cam will strike the pointed projection 19^a of the lever. This operation will force the free end of said lever outwardly, as hereinbefore described, it being observed that the pointed projection 19^a is in 80 a transverse plane nearer to the shaft 16 than that of the pivot 18 of said lever.

Although the shaft 16 is shown and described as tubular, it is evident that said shaft need not be tubular in form, all that is necessary being to provide an opening in the end thereof, which is angular in cross-section and adapted to receive the shank 27 of the key 25, which is adapted to slide therein, said opening and said shank being angular in 90 cross-section. It will also be observed that the rack-bars 13 of the sashes are countersunk therein, and by reason of this fact the sashes may be made to closely fit the frame, and my improved lock may also be applied 95 to other devices, as well as to window sashes and frames.

Having fully described my invention, I claim as new and desire to secure by Letters Patent—

1. A window-sash provided with a rack-bar at one side thereof, and a casing countersunk in the frame of the window adjacent to said sash, a spring-operated shaft passing through said casing and provided with a cam, a lever mounted in said casing and adapted to be operated by said cam, said lever being adapted 105 at one end to operate in connection with said rack-bar, and means for operating said shaft, substantially as shown and described.

2. A window-sash provided with a rack-bar at one side thereof, and a casing countersunk in the frame of the window adjacent to said sash, a spring-operated shaft passing through said casing and provided with a cam, a spring-operated lever mounted in said casing and provided with two parts in connection with which said cam is adapted to operate, said lever being provided at one end with a lug or projection which is adapted to operate in connection with said rack-bar, and means for operating said shaft, consisting of a key which is adapted to be passed through the side of the window-frame, substantially as shown and described.

3. A window-frame provided with the usual sashes, a casing mounted in the frame between said sashes, a spring-operated shaft passing through said casing and provided with a cam, a spring-operated lever mounted 130 in said casing and adapted to be operated by said cam, said lever being provided at one

- end with a cross-head adapted to operate in connection with rack-bars secured to the sashes, and means for operating said shaft, substantially as shown and described.
- 5 4. In a lock, a casing, a spring-operated shaft passing therethrough, and provided with a cam, means for operating said shaft and a spring-operated lever mounted in said casing and adapted to be operated by said cam, said lever being curved and provided with two different parts in connection with which said cam is adapted to operate, substantially as shown and described.
- 5 5. The combination with a window frame and sash, the sash being provided with a rack-bar, of a lock mounted in said frame and comprising a shaft provided with a cam, a lever adapted at two different points to be operated by said cam and to engage with said rack-
- bar, and means for operating said shaft, substantially as shown and described.
6. The combination with a window-frame, of a sash-lock which is mounted therein between the spaces occupied by the sashes, said lock being provided with a lever having a cross-head at one end which is adapted to operate in connection with rack-bars secured to the sashes, and means for operating said lever, substantially as shown and described.
- In testimony that I claim the foregoing as my invention I have signed my name, in presence of the subscribing witnesses, this 14th day of November, 1898.
